AUTOMOBILE SANDING DEVICE

Application filed February 18, 1931. Serial No. 516,553.

Our invention relates to improvements in automobile sanding devices, and the object of the invention is to construct a device which will permit sand being sprinkled upon the road immediately in front of the rear wheels of the vehicle to prevent skidding thereof. A further object is to so construct a device so that the emission of sand may be controlled from the driver's seat of the vehicle, and a still further object is to devise means whereby a substantially uniform quantity of sand is sprinkled on the road in front of each rear wheel.

Yet another object is to devise means whereby the application of the foot brake will, if desired, automatically actuate the device for applying sand to the road, such connection to the foot brake being capable of being disconnected.

With the above and other objects in view which will hereinafter appear as the description proceeds, our invention consists of a sanding device constructed and arranged all as hereinafter more particularly described and illustrated in the accompanying drawing in which:—

Fig. 1 is a side elevation of an automobile, partly in section, showing our device applied thereto.

Fig. 2 is an enlarged fragmentary section through a part of the automobile showing our device.

Fig. 3 is an enlarged horizontal cross section through the line 3—3 Figure 4 showing one of the sand controlling valves, and

Fig. 4 is a vertical section through the line 4—4 Figure 2 showing the sand container.

Like characters of reference indicate corresponding parts in the different views.

A sand container 1 is preferably located immediately behind the front seat of the vehicle and preferably has on its interior a double inclined deflector 2 for deflecting the sand toward the outlet orifices 3 which are located in the bottom of the container 1 in the vicinity of its ends. Gate valves 4 are located immediately below the orifices 3, and the gates 5 of each valve have levers 6 which are swingably mounted on brackets 7 formed

on the gate valve bodies. The free ends of the levers 6 are connected by rods 8 with depending levers 9 mounted on a cross shaft 10 journaled to the floor boards of the car or otherwise suitably mounted in similar manner on the chassis frame.

A third lever 11 also depends from the cross shaft 10, and this lever 11 is connected by a rod 12 with a swingable control lever 13 within reach of the driver of the vehicle.

Sand pipes 14 extend from the gate valves 4 into proximity with the rear wheels of the vehicle and in front thereof, said pipes 14 having flared lower extremities 15.

A forearm 16 depends from the cross shaft 10 to which it is secured and the free end of said arm 16 is connected by a flexible connection 17 with a lower end 18 of a vertically movable plunger 19 within reach of the driver of the car, said plunger being preferably vertically movable in the tube 18 which may be secured so as to protrude down through the footboard of the car. The plunger 19 is provided with a spring 21 by means of which it is held in its uppermost position. The lower end 18 of the plunger 19 is hinged to the main portion of the plunger 19 and when in its uppermost position, as illustrated in Figure 2, such hinge extends into the tube 20 so as to make the plunger rigid. A spring catch 22 is provided for holding the plunger 19 in its lowermost position.

23 is a rod connected at its forward end to the foot brake 24 and slidably mounted intermediate of its length in the bracket 25, said rod 23 having a slot 26 extending therethrough and adapted to receive the lower end 18 of the plunger 19.

Springs 27 are provided for holding the gate valves 5 in their normal closed position, said springs 27 being preferably connected at their forward ends to the levers 6 and at their rear ends to any suitable part of the car.

A cover 28 is provided for the container 1.

If it is desired to apply the sand to the road surface every time the foot brake is applied it is only necessary for the driver

of the car to depress the plunger 19 so that the catch 22 holds it in its lowermost position when the lower end 18 of such plunger 19 will enter the slot 26 in the rod 23, and when the foot brake 24 is applied it will swing the lower end 18 of the plunger 19 forwardly, thus pulling on the flexible connection 17 to the arm 16 and turning the cross shaft 10, with the result that the levers 9 10 will be swung forwardly and through the medium of the connections or rods 8 the levers 6 will be swung in a like direction and the gate valves 5 opened, thus discharging sand through the pipes 14 onto the road in front 15 of the rear wheels of the vehicle.

Where it is desired to apply the sand independently of the application of the foot brake the plunger 19 is not depressed but is in the position illustrated in Figure 2 of the drawing wherein there is no connection between its lower end and the rod 23. Therefore the sand is applied by actuating the lever 13 by pulling it back, thus swinging forwardly the lever 11 and turning the shaft 10 25 which will swing the levers 9 forwardly and thus open the gate valves 5 as above described.

From the above description it will be apparent that we have devised a simple and 30 effective sanding device which will prevent the automobile's skidding and one in which the sand can be applied automatically upon the application of the brake, as well as independently thereof.

35 What we claim as our invention is:

In an automobile sanding device in combination a brake pedal, a sand container having outlet orifices in the vicinity of its ends, a sand controlling valve below each orifice, 40 a pipe leading from each sand controlling valve into proximity with each rear wheel of the vehicle and in front thereof, a sand valve operating lever within reach of the driver of the vehicle for independent operation of the sand valves, connections between the operating lever and the sand valves, an orificed slide rod extending rearwardly from the brake pedal, a plunger having a hinged portion, said plunger normally spring held 45 in the inoperative position, a flexible connection between the hinged portion of the plunger and the connections between the sand valve operating lever and the sand valves, said flexible connection establishing a connection between the brake pedal and the sand valves when the plunger is depressed into the orifice in the slide rod for automatically operating the sand valves upon the application of the brake.
